UNITED STATES PATENT OFFICE

WILLIAM L. BURNER, OF COLUMBUS, OHIO, ASSIGNOR TO THE CASE
MANUFACTURING COMPANY, OF SAME PLACE.

FLOUR-BOLT-BRUSH OPERATING MECHANISM.

SPECIFICATION forming part of Letters Patent No. 645,455, dated March 13, 1900.

Original application filed February 1, 1898, Serial No. 668,764. Divided and this application filed May 13, 1899. Serial No. 716,722. (No model.)

To all whom it may concern:

Be it known that I, WILLIAM L. BURNER, a citizen of the United States, and a resident of Columbus, in the county of Franklin and State of Ohio, have invented certain new and useful Improvements in Flour-Bolt-Brush Operating Mechanism, of which the following is a specification.

This application is a division of my application for Letters Patent for flour sifting, scalping, and grading machines filed February 1, 1898, Serial No. 668,764, wherein is described and claimed means for causing a reciprocating movement of its cleaning-brush to be set up by the vibratory movement of the sieve, such means comprising a pawl carried by one of the relatively-moving parts, an elongated member carried by the other of said parts and upon which the pawl tracks and engages, so as to transmit the impelling movement from the sieve to the brush, and means whereby the pawl reverses automatically, so as to assume alternately the two positions which result in its driving the brush in opposite directions.

My present invention relates to the means employed for reversing the position of the pawl in carrying out the operation above described; and my invention consists in providing at the reversing-points, preferably the points which are reached by the pawl as the brush attains the limits of its opposite movements, trips which engage the pawl and throw it over into the position which will return the brush in the direction opposite to that of the movement which brought the pawl in contact with the trip.

My invention will be fully understood upon reference to the accompanying drawings, forming part of this specification, and in which—

Figure 1 is a vertical transverse section illustrating the application of my invention to a flour-sieve. Fig. 2 is a plan of the parts shown in Fig. 1. Fig. 3 is a perspective view of a brush carrying the automatically-reversing pawl.

A represents a sieve provided with bolting-cloth *a*. B is a brush whose bristles *b* travel be-

neath the bolting-cloth *a* to clear the meshes of the latter. The sieve may be provided with wires *a'*, stretched transversely to the travel of the brush for the purpose of dislodging material accumulated in the brush.

55

C C represent the tracks upon which the brush B travels.

D is an impelling-pawl carried by the brush B and engaging with the elongated member *d*, which is carried by the sieve and upon which the pawl tracks, so that the vibratory motion of the sieve is imparted in one direction to the brush, while the brush by its inertia does not move with the sieve in the opposite direction. The member *d* is preferably in the form of a rack having teeth *d'*, with which the pawl engages.

My present invention consists in mounting the pawl D reversibly upon the brush—as, for instance, by having it project from a shaft 1, trunnioned in brackets 2—and in providing said shaft with tripping-fingers 3 in such positions that they will be respectively engaged by trips 4 at points which will cause the fingers to be engaged by the trips as the brush reaches the limits of its movement. The trips 4 may be of any suitable form, and they are preferably attached at opposite sides of the rack *d*, and the fingers 3 are in different vertical planes, so that they will be respectively engaged by corresponding trips, so that when the reversal of the pawl has been effected by either finger and the brush starts upon its return movement the other finger will pass the trip without interference.

I desire it understood that I do not limit myself to the precise details of the trips shown, as any construction which provides a trip for engagement with and reversal of the pawl as the brush reaches the limits of its movement will be within the purview of my invention.

Having thus described my invention, the following is what I claim as new therein and desire to secure by Letters Patent:

1. The combination, with a sieve and its cleaning-brush; of a device for effecting a reciprocating movement of the brush, comprising an impelling-pawl and an elongated track with which the pawl engages carried by the respective parts, and trips located at 100

points to engage and reverse the pawl as the brush approaches the limits of its movement; substantially as herein explained.

2. The combination, with a sieve and its cleaning-brush; of a device for effecting a reciprocating movement of the brush comprising an impelling-pawl carried by one of said parts, an elongated track with which the pawl engages carried by the other of said parts, fingers connected with the pawl, and trips which engage the respective fingers and reverse the pawl as the brush reaches the limits of its movement.

3. The combination, with a sieve and its

cleaning-brush; of a device for effecting a reciprocating movement of the brush, comprising a pawl carried by a shaft trunnioned on one of the parts, reversing-fingers projecting from said shaft, and a track with which the pawl engages carried by the other part and having at its respective ends, and in different planes, trips which engage the respective fingers as the brush approaches the limits of its movement.

WILLIAM L. BURNER.
